(57) **CLAIM**

The ornamental design for a multi-triangle putter, as shown and described.

DESCRIPTION

FIG. 1 is a front-top perspective view of a multi-triangle putter showing my new design;

FIG. 2 is a front-bottom perspective view thereof;

FIG. 3 is a rear-top perspective view thereof;

FIG. 4 is a front elevational view thereof, where the rear elevational view is mirrored thereto;

FIG. 5 is a right elevational view thereof;

FIG. 6 is a left elevational view thereof; and,

FIG. 7 is a top plan view thereof, where the bottom plan view is identical thereto.
